US00D876208S

(12) **United States Design Patent** (10) **Patent No.:** **US D876,208 S**
(45) **Date of Patent:** **** Feb. 25, 2020**

(54) **WINDING CORE**

(71) Applicant: **Souhegan Wood Products, Inc.**,
Wilton, NH (US)
(72) Inventor: **Randolph A Dunn**, Wilton, NH (US)
(73) Assignee: **Souhegan Wood Products Inc.**, Wilton,
NH (US)

(**) Term: **15 Years**

(21) Appl. No.: **29/616,803**

(22) Filed: **Sep. 8, 2017**

(51) **LOC (12) Cl.** **08-05**
(52) **U.S. Cl.**

USPC **D8/358**

(58) **Field of Classification Search**

(57)

CLAIM

The ornamental design for a winding core, as shown and described.

DESCRIPTION

FIG. 1 is a 3-dimensional view of a winding core, showing our new design;

FIG. 2 is a front elevation view (rear is the same) thereof;

FIG. 3 is a side elevation view (opposite side is the same) thereof;

FIG. 4 is a top plan view thereof; and,

FIG. 5 is a bottom plan view thereof.

The broken lines shown in the drawings depicts portions of the winding core that form no part of the claimed design.
